UNITED STATES PATENT OFFICE.

GUSTAV F. RICHTER, OF BROOKLYN, NEW YORK.

SURGICAL AND DENTAL INSTRUMENT.

Application filed May 25, 1921. Serial No. 472,366.

To all whom it may concern:

Be it known that I, GUSTAV F. RICHTER, a citizen of the United States, residing in the borough of Brooklyn, city and State of 5 New York, have invented the following described Improvements in Surgical and Dental Instruments.

My invention relates to surgical and dental instruments having a tong-action like 10 hinged retractors, dilators and the like, and more especially mouth gags. Such instruments are commonly provided with latches for retaining them in operating position, expanded or contracted as the case may be, but 15 so far as I am aware all such latches of general application are encumbered by certain undesirable features inherent in them. Some are cumbersome and more or less interfere with the work of the surgeon or dentist 20 and some are adapted to lock only in one position and hence are not suited for every condition encountered; others are adjustable, that is to say are adapted to hold the tongs expanded (or contracted) in different degrees, but act only by definite and relatively 25 large steps like a pawl and rack bar which is a common form of latch in this art, so that the operator is not always able to stop the instrument in exactly the position he wishes 30 it and the instrument must be expanded (or contracted) still farther to release it. The object of my invention is to provide such instruments with a latch that is at once convenient and out of the way and unencumbered with such characteristics.

The accompanying drawings show the invention embodied in the form of a mouth gag to which it is especially applicable, Fig. 1 being a perspective of the same, Fig. 2 an 40 end view of the gag partly in section, and Fig. 3 a modified form of the device of the preceding figures.

The curved mouth members 1 and 2 of the gag are pivotally united at 3 and 4 adjacent their ends; beyond the pivot 4 integral extensions 5 and 6 of the mouth members terminate in handles or grips 7 and 8 bent outwardly in right angles thereto for expanding the gag. It will be understood that 45 in use the extensions at 12 on the mouth members are inserted between the patient's jaws so as to rest on the teeth; by compressing the handle levers 7 and 8 the gag is expanded and the patient's mouth forced 50 open. To hold the gag expanded I provide a latch comprising a cam 14 on one of the

instrument members to cramp or bind against a co-acting arcuate member 15 mounted on the other instrument member. The depth or radius of curvature of the cam 50 shown, which is hinged on the pintle 13, increases gradually from A to B so that the arcuate member slides easily over the cam as the instrument handles are pressed together but is automatically seized as the 55 mouth members 1 and 2 tend to close. The cam therefore automatically locks the arcuate member against reverse movement and the instrument in operating position. The handle 16 is arranged for manually releasing the arcuate member against the pressure of a flat spring 17 fastened on the inside of one of the handles and normally urging the cam in the locking direction. Either or both the arcuate member and the cam are knurled 70 or provided with serrations at 18 to assure positive engagement between them and the movement of the cam to locking position. Preferably the cam 14 is disposed in a central slot in the handle extension 6, into both 75 walls of which the pintle 13 extends, and the arc member 15 is made a rigid part of the opposite handle extension and is curved on the pivot 4 as a center so as to slide in the opposite end of the cam slot, and preferably 80 in engagement with the adjacent end wall thereof. I prefer to make arc member 15 as a separate piece and secure the same to its instrument member; not only does this simplify the fabrication of the instrument 85 but also I am enabled to stamp out the part 90 15 from mild steel and secure the necessary hardness in it by case-hardening a few hours. Should this attachment lose its rigidity at any time its engagement with the end wall 95 of the slot permits the cam 14 to clamp it against this end wall as a fixed abutment and thus continue the locking engagement substantially without change. As shown in Fig. 3, the arcuate member 15 may be hinged 100 to its instrument handle initially in which case the cam clamps it against the slot end wall from the beginning. With either construction, it will be observed, the arrangement of the cam 14 and arc member 15 in 105 the slot in the handle extension affords a permanently rigid abutment for the arc member, initially or in the case of emergency, and a strong construction not likely to get out of order or deteriorate with use 110 and furthermore an arrangement wherein all the latch parts are located out of the way

of the operator and in such positions as not to interfere with the application of the instrument to the patient.

It will be apparent that the gag may be readily expanded, the arcuate member riding easily over the cam as the mouth members are opened by compressing the handles; as soon as the handles are released, however, the pressure of the patient's jaws on the mouth members tending to close the latter and withdraw the arcuate member from the slot, brings the locking cam into locking action and holds the gag expanded in practically the exact position to which it is brought by the operator, there being practically no recession. In order that the gag may be easily opened and closed for cleaning, etc., the rear extension 19 of the cam 14 on which the spring 17 bears, may be so arranged that when the cam has been withdrawn from the arc member 15 to some extent beyond its releasing position, the spring tends to depress the extension on the opposite side of the hinge pin 13 as shown in Fig. 3, thus farther withdrawing the cam. The projecting pin 20 on the cam limits this movement by striking the handle extension. By withdrawing the cam 14 as far as possible, in this construction, it may be left temporarily in an open or releasing position and from this position may be restored to automatic action by a manual movement toward the arc 15.

It will be apparent that my invention embodies none of the disadvantages that I have mentioned hereinbefore and that while I have shown and described it as embodied in a mouth gag to which it is particularly applicable, it is also applicable to other surgical and dental instruments as appears from the following claims.

Claims:

1. The combination with relatively pivoted members of a surgical or dental instrument, of a latch therefor comprising a cam mounted on one of the instrument members and a co-operating member projecting from another of the pivoted members, the cam binding against the projecting member to lock the instrument members against reverse movement.

2. In an instrument of the kind described, the combination of the tong-like members, one of which is provided with a slot, a cam mounted in said slot and a co-operating

latch member projecting from the other or said tong-like members and sliding in the slot, whereby the cam binds the co-operating latch member to lock the instrument in operating position. 60

3. In an instrument of the kind described, the combination with the tong-like members and the handles for the same, one of the handles being provided with a slot, of an eccentric cam pivoted in one end of said slot, a co-operating latch member projecting from the other handle and sliding in the other end of the slot, whereby said cam binds against the co-operating member to lock the instrument in operating 65 position, and spring means normally holding the cam against the co-operating member. 70

4. In an instrument of the kind described, the combination with the tong-like members thereof, one of which is provided with a locking wall, of an eccentric cam pivoted to the member having the wall, and a co-operating latch member attached to the other of said instrument members and sliding between said cam and wall, whereby said co-operating member may be cramped against said wall to lock the instrument in operating position. 75

5. In an instrument of the kind described, the combination with the tong-like members thereof, of an eccentric cam pivoted to one of the instrument members, a co-operating latch member projecting from the other of said instrument members whereby 80 said cam binds against the co-operating member to lock the instrument in operating position, and spring means normally holding the cam against the co-operating member and also adapted to hold the cam 85 retracted. 90

6. In a surgical instrument, the combination of pivoted tong-like members, and a latch comprising a cam mounted on one of said members, and a co-operating arcuate member projecting from the other of said tong-like members, the cam binding against said arcuate member to lock the instrument members in operating position and one of the latch members being roughened to assure positive engagement between them. 100

In testimony whereof, I have signed this specification.

GUSTAV F. RICHTER,
